BRAKE

Creed C. Elliott, Richmond, Va.

Application February 6, 1933. Serial No. 655,529

1 Claim. (Cl. 188—24)

This invention relates to brakes especially adapted for children's toys and has for the primary object, the provision of a device of the above stated character which will be efficient in operation, will permit a child to stop or have complete control of a toy of the wheel type and consists of a minimum number of parts to permit manufacturing and sale costs to be kept at a minimum upon toys when thus equipped.

10 With these and other objects in view this invention consists in certain novel features of construction, combination and arrangement of parts to be hereinafter more fully described and claimed.

15 For a complete understanding of my invention, reference is to be had to the following description and accompanying drawing, in which

Figure 1 is a side elevation illustrating a toy with a brake applied thereto and constructed in accordance with my invention.

20 Figure 2 is a front elevation illustrating a toy.

Figure 3 is a bottom plan view illustrating the mounting of the brake to the toy.

25 Figure 4 is a perspective view illustrating the brake removed from the toy.

Referring in detail to the drawing, the numeral 1 indicates a child's toy and of the type wherein three wheels are employed, a pair of wheels, as shown at 2, being arranged at the rear of the 30 main frame 3, while the third wheel is indicated by the character 4 and is carried by a steering fork 5 mounted to an upright 6 of the main frame. The steering fork carries the usual hand grips 7 whereby the fork may be turned for the purpose 35 of steering the front or third wheel. The main frame 3 has mounted thereon a suitable platform 8 on which a child may stand when riding the toy.

The foregoing description relates to a construction of toy forming the subject matter of a 40 co-pending application and to which the present invention is applied.

Brackets 9 and 10 are secured to the under face of the platform 8 and the bracket 9 has pivoted thereto a lever 11, one end of which is bent in 45 hook formation, as shown at 12, and pivoted to the forward end of a rod 13 slidably supported by the bracket 10. The other end of the lever 11 is connected to a post 14 by a pin and slot connection 15 and the post extends through an opening in the platform and carries a pedal 16 at its 50 upper end disposed in a plane slightly above the platform so that a child may tread upon the pedal for the purpose of effecting movement to the lever and consequently movement to the rod 13. A 55 collar 17 is secured to the rod 13 and spaced from

the bracket 10 and interposed between the bracket 10 and the collar 17 is a coil spring 18 for the purpose of normally urging the rod 13 forwardly into non-brake applying position. The rod 13 rearwardly of the bracket 10 is inclined upwardly 60 to extend through the main frame 3 and carries a U-shaped bracket 19 and the latter has secured thereto a brake beam or rod 20 which extends transversely of the main frame and slides upon the upper edge thereof. Grooved rollers 21 forming 65 brake shoes are journaled on the beam 20 and arranged in advance and in alignment with the rear wheels 2 so that when the rod 13 is moved rearwardly by a child pressing upon the pedal 16 brings the brake shoes in engagement with the 70 wheels and consequently retards or stops the toy.

While I have shown and described the preferred embodiment of my invention, it will be understood that minor changes in construction, combination and arrangement of parts may be made 75 without departing from the spirit and scope of my invention, as claimed.

Having described the invention, I claim:

In combination with a toy having a frame supported by wheels and a platform, a brake rod 80 slidably secured to the under side of the platform, tension means to normally urge the brake rod in one direction, a lever pivoted to the platform and having a hook-shaped end pivoted to the brake rod, a post pivotally and slidably connected to 85 the lever and extending through the platform, a pedal carried by the post, said rod having a portion thereof curved to extend upwardly through the frame, a brake beam connected to the rod and slidable upon the frame, and grooved rollers 90 journaled on the brake beam and arranged in advance and in alignment with the wheels.

CREED C. ELLIOTTE.
